UNITED STATES PATENT OFFICE

PETER B. PENKOFF, OF TOLEDO, OHIO

DESIGN FOR A DANCING DOLL

Application filed March 24, 1930. Serial No. 35,015. Term of patent 7 years.

To all whom it may concern:

Be it known that I, PETER B. PENKOFF, a citizen of the United States of America, residing at Toledo, Lucas County, Ohio, have invented a new, original, and ornamental Design for Dancing Doll, of which the following is a specification, reference being had to the accompanying drawing, forming a part thereof.

Fig. 1 is a front elevation of the dancing doll; and

Fig. 2 is a side elevation of the dancing doll.

The section lines are for the purpose of indicating color only.

I claim:

The ornamental design for a dancing doll as shown and described.

PETER B. PENKOFF.
